(57) **CLAIM**

The ornamental design for a vehicle handle, as shown and described.

DESCRIPTION

1. Door handle for vehicles
  2. Door handle for vehicles
  - 1.1 : Perspective
  - 1.2 : Front
  - 1.3 : Back
  - 1.4 : Left
  - 1.5 : Right
  - 1.6 : Top
  - 1.7 : Bottom
  - 1.8 : Perspective view in a configuration of use
  - 2.1 : Perspective
  - 2.2 : Front
  - 2.3 : Back
  - 2.4 : Left
  - 2.5 : Right
  - 2.6 : Top
  - 2.7 : Bottom
  - 2.8 : Perspective view in a configuration of use
- No claim is made to the features in broken lines; The characteristic feature of the design is the hexagonal shape.
